No. 36,575.

Patented October 6, 1903.

UNITED STATES PATENT OFFICE.

JOHN ZIPP, OF CHATTANOOGA, TENNESSEE.

DESIGN FOR A WASHBASIN.

SPECIFICATION forming part of Design No. 36,575, dated October 6, 1903.

Application filed April 15, 1903. Serial No. 152,807. Term of patent 7 years.

To all whom it may concern:

Be it known that I, JOHN ZIPP, a citizen of the United States, residing at Chattanooga, in the county of Hamilton and State of Tennessee, have invented a new, original, and ornamental Design for Washbasins, reference being had to the accompanying drawing.

In said drawing the figure is a perspective of a washbasin embodying my new and ornamental design.

What I claim as new, and desire to secure by Letters Patent, is—

The ornamental design for a washbasin, as shown.

In testimony whereof I have signed my name, in presence of two witnesses, this 8th day of April, 1903.

JOHN ZIPP.
